SHRINKING HAMMER FOR SHEET METAL WORKING

Darrell D. Schmeling, Watertown, S. Dak.

Application November 3, 1950, Serial No. 193,808

7 Claims. (Cl. 81—15)

1

This invention relates to shrinking hammers for sheet metal working.

In sheet metal working, such as in the straightening of automobile bodies, etc. where the metal has previously been distorted and expanded to some extent, the metal is commonly returned to its original shape by a shrinking process. This process includes the intense heating of a very local area of the portions of the metal previously distorted and, while the metal is still hot, hammering it into its original shape with what is known as a shrinking hammer. By heating a small and very local area intensely, the respective molecules of the metal within the center of that area tend to disperse and move into a more compact relation with respect to each other around the periphery of the area and adjacent the molecules of the unheated portions. Then when the metal cools, the central portion of the heated area contracts and shrinks rapidly, thereby tending to return the surface of the metal to its original smooth condition.

The process described above has previously been accomplished by one man applying an acetylene torch or similar heating element to the local area of metal to be shrunk and by a second man following him with an anvil and a hammer with which the metal is hammered into shape. The anvil, of course, must be held behind the metal while the hammer is applied to its opposite side. My invention is directed toward the simplification of this operation in so far as efficiency is concerned.

It is a general object of my invention to provide a novel and highly improved shrinking hammer of cheap and simple construction and of efficient operation.

A more specific object is to provide a shrinking hammer of increased efficiency whereby one man may readily and easily perform a metal shrinking operation which previously required the labor of at least two men.

Another object of my invention is to provide a shrinking hammer which will permit one man to perform a complete metal shrinking operation which is continuous in nature in order to effect more efficient and economical sheet metal working.

These and other objects and advantages of my invention will more fully appear from the following description made in connection with the accompanying drawings wherein like reference characters refer to the same or similar parts throughout the several views and in which:

Figure 1 is a side elevational view of one embodiment of my invention shown in position for proper use to shrink a piece of metal.

Figure 2 is a bottom elevational view of the same.

2

Figure 3 is a fragmentary sectional view taken along line 3—3 of Figure 2.

One embodiment of my invention may include as shown in Figures 1-3, a shank 5 having fixedly mounted on one of its end portions a rigid non-combustible block 6. As shown the shank 5 is preferably made of wood while the block 6 is preferably constructed of metal. The block 6, as shown, has a generally cylindrically shaped portion 7 extending downwardly therefrom and carrying a relatively broad and flat head 8 at its lower end. The head 8 has a smooth pounding surface 9 which faces downwardly and has a peripheral recess 10 formed therein. Extending upwardly from the block 6 is an elongated and tapering pecking head 11.

Mounted within the handle portion 12 of the shank 5 is a conduit 13 which is preferably made of metal. As shown this conduit 13 extends forwardly to a point adjacent the block 6 from which it extends downwardly and passes through the central portion of the cylindrically shaped portion 7 and terminates with a nozzle 14. This nozzle 14 is disposed within the confines of the recess 10 of the head 8 as best shown in Figure 2. It also terminates in substantially the same plane as the smooth pounding surface 9 of the head 8. As best shown in Figure 2 its orifice 15 is of a relatively small diameter.

The rear end portion of the conduit 13 has connected thereto by means of a clamp 16, a flexible conduit 17, the other end of which is connected to a source of highly-inflammable gas (not shown) such as acetylene. Through this conduit 17 the acetylene gas may be forced through the conduit 13 and outwardly through the nozzle 14 to provide, when lighted, a flame 18 of high intensity. This flame 18, as best shown in Figure 1, is directed downwardly to play upon the distorted sheet metal surface indicated in Figure 1 as 19.

In operation the metal worker will cause the flame 18 to play upon the distorted metal 19 for a brief period at the proper distance therefrom so as to obtain maximum heat from the flame. After the distorted portion 19 has been sufficiently heated to cause the metal to shrink the metal worker will tap that area gently with the smooth pounding surface 9 of the head 8 to cause the metal to resume its original shape. While the distorted portion 19 is being hammered into its original shape as a result of the shrinking and the gentle tapping, the area of sheet metal immediately adjacent thereto and ahead thereof will be heated by the flame 18 preparatory to working the same. Thus it can be readily seen that the metal worker will thereby be permitted to work forwardly continuously without interruption. With one hand he may

hold the anvil behind the sheet metal to be worked, and with the other he may direct the head 8 and the flame 18 continuously along the surface. Thus it is possible to eliminate one man's labor by utilizing my invention.

In addition to the above, a metal worker may attain increased efficiency in his work since he will have quicker access to the heated area with this hammer than he would have if another man were heating the area for him. By utilizing my hammer, the metal worker may strike the metal previously heated almost the instant immediately after it has been heated. When two men are required for this operation, it is first necessary for the man with the acetylene torch to move away from the heated area to provide room for the necessary movement of the man with the hammer and anvil.

It should be noted that by positioning the nozzle 14 within the periphery of the head 8, that the metal worker is assured that the sheet metal next to be hammered will be heated properly. In other words, the source of heat is maintained as closely as possible to the area being straightened. It should also be noted that the acetylene gas is supplied to the nozzle with a minimum of inconvenience to the metal worker by transferring the same directly through the shank 5.

Thus it can be seen that I have provided a shrinking hammer of cheap and simple construction which eliminates the labor of one man and which will permit a single sheet metal worker to readily and easily perform a metal shrinking operation in a continuous manner.

It will, of course, be understood that various changes may be made in the form, details, arrangement and proportions of the parts without departing from the scope of my invention.

What I claim is:

1. A shrinking hammer for sheet metal working having in combination, a shank, a rigid, non-combustible block fixedly mounted on one end portion of said shank, at least a portion of said block having a head thereon, said head having a continuously flat outer surface, and a nozzle carried by said shank, said nozzle being adapted for connection to a source of highly combustible gas and being arranged to direct a burning flame of such gas adjacent to but not directly beneath said head whereby as said head is applied to a section of sheet metal to work the same an area of such metal immediately adjacent thereto will be heated preparatory to being worked by said head.

2. A shrinking hammer for sheet metal working having in combination, a shank, a metal block fixedly mounted on one end portion of said shank, at least a portion of said block having a head thereon, said head having a continuously flat outer surface disposed in a plane substantially parallel to said shank, and a nozzle carried by said shank, said nozzle being adapted for connection to a source of highly combustible gas and being arranged to direct a burning flame of such gas adjacent to but not directly beneath said head whereby as said head is applied to a section of sheet metal to work the same an area of metal immediately adjacent thereto will be heated preparatory to being worked by said head.

3. A shrinking hammer for sheet metal working having in combination, a shank, a metal head fixedly secured to one end portion of said shank, said head having a continuously smooth exterior pounding surface, and a nozzle carried by said

5 shank, and disposed adjacent said pounding surface, said nozzle being adapted for connection to a source of highly combustible gas and being arranged to direct a burning flame of such gas adjacent to but not beneath said head whereby as said head is applied to a section of sheet metal to work the same an area of such metal immediately adjacent thereto will be heated in preparation for being worked by said head.

4. A shrinking hammer for sheet metal working having in combination, a shank, a metal head fixedly secured to one end portion of said shank, said head having a continuously smooth downwardly facing pounding surface, and a nozzle mounted on said head adjacent its periphery, said nozzle having conduit means connected thereto for connection with a source of highly combustible gas and being directed downwardly toward a point beside said head whereby as said head is applied to a section of sheet metal to work the same, said nozzle may direct a burning flame to an area of such metal immediately adjacent to prepare the same to be worked by said head.

5. A shrinking hammer for sheet metal working having in combination, a shank, a rigid, non-combustible head fixedly secured to one end portion of said shank, said head having a continuously smooth downwardly facing pounding surface, and a nozzle carried by said shank and disposed adjacent the periphery of said head, said nozzle having conduit means connected thereto for connection with a source of highly inflammable gas and being directed downwardly toward a point beside said head whereby as said head is applied to a section of sheet metal to work the same, said nozzle may direct a burning flame to an area of such metal immediately adjacent thereto to prepare the same to be worked by said head.

6. A shrinking hammer for sheet metal working having in combination, a shank, a rigid, non-combustible block fixedly mounted on one end portion of said shank, said block having a neck portion and a head portion, said head portion having a continuously smooth downwardly facing pounding surface, a nozzle carried by said shank and disposed adjacent the periphery of said head portion and slightly above said pounding surface, said nozzle being directed downwardly toward a point immediately beside said pounding surface whereby as said head is applied to a section of sheet metal to work the same, said nozzle may direct a burning flame to an area of such metal immediately adjacent such section to prepare the same to be worked by said pounding surface, and conduit means connected to said nozzle for connecting the same with a source of highly inflammable gas, said conduit means extending through said neck portion.

7. The structure defined in claim 6 said shank comprising a handle and a substantial portion of said conduit means being carried within said handle to facilitate the manipulation of the shrinking hammer.
